CLAIM

The ornamental appearance of a one-piece cushion with base and nozzles, as shown and described.

DESCRIPTION

FIG. 1 is a perspective view of a one-piece cushion with base and nozzles according to our design;
FIG. 2 is a front view thereof; and,
FIG. 3 is a top view thereof.

Throughout the various Figures of the drawings, certain views are not provided. The omission of a particular view is intended to convey that the element(s) depicted is/are plain and unornamented in that omitted view, or that the particular ornamental appearance in that view is simply not claimed. Where included, broken lines show environmental structure and form no part of the claimed design.
